UNITED STATES PATENT OFFICE.

CLAUDE I. HAINES AND JOHN STANLEY BOWER, OF ALEDO, ILLINOIS.

TRAIN-STOPPING DEVICE.

Application filed October 5, 1922. Serial No. 592,636.

To all whom it may concern:

Be it known that we, CLAUDE I. HAINES and JOHN STANLEY BOWER, citizens of the United States, and residents of Aledo, in the county of Mercer and State of Illinois, have invented a new and useful Improvement in Train-Stopping Devices, of which the following is a full, clear, and exact description.

Our invention relates to improvements in train stopping devices, and it consists in the combinations, constructions, and arrangements herein described and claimed.

An object of our invention is to provide a device of the character described in keeping with the requirements of modern safety, in which manual control is entirely obviated.

A further object of our invention is to provide a device of the character described which may cause the train to come to a dead stop whenever the train has passed a block that has been set against passage of the train.

A further object of our invention is to provide a device of the character described which must be set manually after its operation before the train can proceed.

A further object of our invention is to provide a device of the character described which will work as effectually when the train is moving backward as when the train is moving forward.

A further object of our invention is to provide a device of the character described which may be set by the engineer of the train so that the train may pass through a block that has been set against the passage of trains, as in the case of special orders.

Other objects and advantages will appear in the following specification, and the novel features of the invention will be particularly pointed out in the appended claims.

Our invention is illustrated in the accompanying drawings forming part of this application, in which

Figure 1 is a side elevation of an embodiment of our invention applied to the ordinary type of steam locomotive,

Figure 2 is a partial top plan view of the mechanism illustrated in Figure 1,

Figure 3 is a sectional view along the line 3—3 of Figure 2, and

Figure 4 is a side elevation of a portion of the mechanism illustrated in Figure 1, in operation.

In carrying out our invention, we make

use of the ordinary type of steam locomotive 1, such as shown in dotted lines in Figure 1. The locomotive 1 is provided with a steam valve 2 which controls the flow of steam to its steam chest 3, the throttle rod 4 controlling the valve 2 and an air brake control line 5—5'.

A pair of pillar blocks 6 and 7 are mounted upon the guide members 8 and 9, respectively. The pillar blocks 6 and 7 are provided with co-axial bearing portions therethrough. A horizontal crank shaft 10 is rotatably mounted on the bearing portions of the pillar blocks 6 and 7, as shown in Figure 2. One end of the crank shaft 10 is bent laterally at 11, thus providing a lever portion 12, which is disposed substantially above the cross head guide bars 13 and 14 of the locomotive 1.

A pair of supporting plates 15 and 16 are secured by means of bolts or the like to the outer surfaces of the guide bars 13 and 14 respectively, as shown in Figure 1. The plates 15 and 16 are each provided with a square opening 17 therethrough. A vertical slide bar 18 substantially square in the cross section is slidably mounted in the opening 17 of the plates 15 and 16, the bar being arranged to closely fit the opening 17 so that it may not turn. The lower end of the vertical bar 18 is provided with a shoe 19 integral therewith, and having an arcuate surface 20 on its lowermost face. The vertical slide bar 18 is further provided with a laterally bent portion 21, extending in perpendicular relation with the shoe 19. This may be clearly seen in Figure 2.

The vertical slide bar 18 is provided with a pair of restricted portions 22 and 23 intermediate its length, and arranged so that the restricted portions 22 and 23 may be moved into registration with the plates 15 and 16 when the slide bar is elevated, thereby permitting the slide bar 18 to be rotated at will, and the laterally bent portion 21 moved toward or away from the locomotive as shown in dotted lines in Figure 2, for a purpose hereinafter described.

The crank shaft 10 is provided with a crank portion 24, upon which a suitable sleeve 25 is carried. A tension spring 26 is connected at one end with the sleeve 25 as shown at 27, and at its opposite end 28 to a T-shaped supporting member 29. The supporting member 29 is securely fixed to the forward end of the boiler support of the

locomotive 1. The crank shaft 10 is further provided with a pair of radially extending spaced apart arms 30 and 31.

The arm 31 has pivotally connected thereto at 32 a rod 33 which is adapted to slide within a tubular casing 34 secured by brackets 35 to the outer boiler sheet of the locomotive 1. The opposite end of the rod 33 is connected to a cable 36. The cable 36 extends upwardly and over a guide pulley 37 supported above the top of the outer boiler sheeting by means of a bracket 38.

The opposite end 39 of the cable 36 is connected to a break joint generally indicated at 40, which connects the throttle rod 4 with the valve stem 41 of the steam control valve 2.

The break joint 40 consists of an arm 42 which is pivotally mounted at one end of the valve stem 2, as shown at 43, and a second arm 44 pivotally mounted at 45 to an upwardly extending portion of the throttle rod 4. The rod 44 is hingedly connected at 46 to the rod 42 to form a joint which may be broken by lifting the rod 44 as by means of drawing it on the cable 36.

The radial arm 30 on the crank shaft end is pivotally connected at 47 to a connecting rod 48, the outer end of which is pivotally connected at 49 to the stem 50 of a three-way valve 51 disposed in the air brake line of the air brake control 5—5'. The valve 50 is so connected in the brake line 5—5' that movement in one direction of the valve stem 50 will cause the air to escape from the brake line and apply the brakes to the train, while the normal position of the valve stem 50 would merely maintain the brake line in an inoperative position and hold the brakes free from engagement with the wheels.

It should be explained here that the lever portion 12 of the crank shaft 10 exactly over-lies and rests upon the laterally bent portion 21 of the slide bar 18 when that bar is turned in the position shown in full lines in Figure 2.

From the foregoing description of the various parts of the device, the operation thereof may be readily understood. In using our train stopping device, it is necessary to employ a block which is shown at 53 having inclined end walls 54 and 55. The block 53 may be connected to the ordinary semaphore block signal or railroad signal device so that it may be moved into registration with the shoe 19 when it is desired that the locomotive should not pass a block.

It is well known that occasionally an engineer may not see the signal or may be injured and unable to see the visual signal.

It is for such cases as this that our present invention is provided, as well as for the purpose of rendering the present block system absolutely positive in its operation.

Let us assume that the locomotive 1 is ap-

proaching a section of track upon which another train is at present running, and that the block 53 has been elevated to that position shown in Figure 1 as a signal that the locomotive must not pass. The semaphore signal of course will operate at the same time that the block 53 is moved, but for the purpose of the explanation let us assume that the engineer does not see the semaphore. The locomotive 1 continues to move forward until the shoe 19 engages the block 53. As the shoe 19 moves into contact with the block 53 the rod 18 will move upwardly in the openings 17 of the plates 15 and 16. As the rod 18 is elevated it will also move the lever portion 12 of the crank shaft 10, thus causing the crank shaft to rotate in the pillar block 6 and 7. It will be noted upon inspection of Figures 1 and 2 that the spring 26 is disposed so as to draw the lever 12 quickly in an upward direction when the crank portion 24 has moved beyond its dead center relative to the portion 28. This will cause a quick movement of the entire crank shaft 10 and the radial arms 30 and 31 integral therewith.

As the arm 31 moves, the rod 33 will slide within the casing 34 and draw the cable 36 downwardly. As the cable 36 moves downwardly, its opposite end 39, which is connected to the arm 44 of the break joint 40, will swing and the break joint 40 will open. This will move the valve stem 41 and close the steam valve 2. As the radial arm 30 moves, the connecting rod 48 will cause the stem 50 of the valve 51 to move and the valve to operate. The operation of the valve 51 will permit air in the brake line 5—5' to escape and the brakes will be set, thus stopping the train. It should be understood at this time that the opening to which air escapes from the valve 51 may be controlled by a needle and pin-hole construction, so that the brakes may not set too quickly and the operation of the brakes may be adjusted manually.

It will be seen, therefore, that the introduction of the block 53 to engagement with the rod 18 will cause the locomotive to stop.

In order to again operate the locomotive, it is necessary for the engineer to step out of the cab and manually throw the lever portion 12 of the crank shaft 10 downwardly beyond the dead center of the crank portion 24 and the portion 28 of the support 29, which will cause the spring 26 to hold the lever 12 in close engagement with the top of the vertical slide rod 18. The cable 36 will thereupon lie slack and permit the arm 40 to be manually reset in an operative position.

Means for preventing the rod 18 from dropping out of engagement with the plates 15 and 16 is provided in a pin 57.

It will be noted that the supporting member 29 besides serving as a means for sup-

porting one end of the spring 26 as shown at 28, will serve as a stop to limit the rotation of the crank shaft 10. This is shown in Figure 3 where the crank 24 is represented in dotted lines, and rests upon the forward end of the supporting member 29.

I claim:

The combination with a steam locomotive having a throttle valve and a throttle rod for 10 operating said throttle valve, of a break joint disposed between said throttle rod and

said throttle valve, and at a point exterior of the cab of said locomotive, a cable connected with said break joint, and means associated with said locomotive and with the track upon which said locomotive is disposed for operating said break joint through said cable to open the joint, thereby operatively disconnecting said throttle rod from said throttle valve.

CLAUDE I. HAINES.
JOHN STANLEY BOWER.
